FILM MOTION FILTER

Harold J. Hasbrouck, Jr., Merchantville, N. J., assignor to United Research Corporation, Burbank, Calif., a corporation of Delaware

Application March 28, 1936, Serial No. 71,532

13 Claims. (Cl. 271—2.3)

This invention relates to talking motion picture apparatus and particularly to the film drive portion of the sound recording or reproducing unit wherein the motion of the film past the 5 translation point is maintained constant. It is well understood that a necessary prerequisite for perfect sound recording and reproduction is that the film be advanced at a constant and uniform speed through the light beam, the point of contact between the film and beam being known as 10 the translation point. Stabilizing devices such as flywheels have been and are employed for stabilizing the motion at this point against the effects of starting surges, take-up reel jerks, mechanical faults of the driving mechanism, or other 15 extraneous causes of speed variations. The flywheels may be supplemented by other mechanical filter elements having, for example, elastic and/or resistive characteristics to aid in stabilization.

In the types of filter elements having mechanical resistance are included dash pots employing viscous mediums such as oil. Such an oil dash pot has heretofore been used to control the 25 movement of a resilient restoring element acting on a loop in the film between the drive sprocket and the flywheel roller which guides the film at the translation point.

The present invention is directed to an improvement in a filter of this type, this improvement consisting of a particular form of sliding friction as the damping element instead of a viscous friction such as produced by oil in the dash pot type of damping element. Many advantages of the sliding friction damper, if designed in accordance with this invention, are found over the viscous damper, some of which are, freedom from attention, independence of temperature changes, no oil leakage problem, 40 and less counterforce during rapid displacements, thereby permitting an adjustment which results in a more rapid decay of filter oscillations initiated, for example, by the starting surge.

In the normal sound unit, some of the causes 45 of speed variations not minimized by the flywheel and oil dash pot may be traced to the starting surge, film reel take-up jerks, and the variations in friction of bearings due to poor maintenance. These causes of speed variations 50 produce different rates or velocities of film speed changes which lie within determinable frequency limits. It has been found in the use of an oil dash pot damper in a filter having a low period that, if the damper is adjusted to provide 55 the proper damping to quickly dissipate the

oscillations initiated by the starting surge, which generally produces a low velocity variation, it will offer such a large counterforce during any later rapid displacements or variations that the angular velocity of the flywheel may be substantially altered or the film caused to slip on its roller or drum. Also if it were adjusted properly for the rapid variations, it would be insufficient to dampen out the slower variations.

To avoid flywheel speed variations therefore, 10 the damper should not offer a counterforce so large as to prevent the moving elements of the filter from promptly accommodating the changed length of loop between the drive sprocket and the drum of the flywheel caused by rapid variations nor, should it be so small as to permit the moving elements to oscillate for an appreciable time. If a viscous type of damper is adjusted to provide sufficient damping of the fundamental period of the filter to quickly dissipate the oscillations caused by the starting surge, then sudden film speed changes produce sufficient counterforce to permit a sudden transfer of energy to the flywheel and consequently appreciably alter the speed of the film at the translation 25 point. This is because with viscous dampers the counterforce increases directly with velocity, particularly within the velocity limits required by film drive filters, while for further increased velocities a counterforce proportional to higher 30 powers of the velocity may be produced caused by the onset of turbulence in the fluid.

It has also been found that the ordinary or usual type of sliding friction has a static friction greater than its initial kinetic friction with the 35 result that the force required to start it in motion is considerably greater than the force required to maintain movement thereafter, the transition occurring quite rapidly. Such types of sliding friction are not suitable for the invention since damping would only be accomplished after a surge of sufficient force was introduced to overcome the static friction counterforce. There would thus be set up a series of transient surges or parasitic oscillations 40 caused by such force acting on the film elastance and flywheel mass. It has been discovered therefore that the static friction should be substantially zero or negligible compared with the operating kinetic friction.

As stated above, if the viscous damper produced sufficient damping at the low velocities, it would produce entirely too great a counterforce at the higher velocities, and if it had the proper damping effect at the higher velocities, 55

this effect would be insufficient at the lower velocities. Similarly, for the usual type of sliding friction, if the static friction force were made of the proper value, the counterforce of friction would be too low to damp out the oscillations over the critical range while, if the latter were correct, the former would be too high with the parasitic oscillations occurring. What is desired, therefore, is a damper having a counterforce which is substantially constant with velocity above the critical range of film variation velocities and which has a static friction of substantially zero.

For instance, to illustrate with a particular case, a starting surge may result in a shortening of the film loop, due to the film being taken out of the loop faster than it is fed thereto by the flywheel roller during its acceleration up to normal film speed. The result is the storing of energy in the tensioning means beyond that required for normal film speed. This energy is released when the drum has reached normal speed and, without a damper, this energy release will maintain excess tension in the film and continue to accelerate the flywheel. The result of this acceleration is a transfer of energy from the spring to the flywheel which increases the loop beyond its normal size as more film is fed into it by the drum than is taken out by the drive sprocket.

This inter-transfer of energy between the tensioning means and flywheel produces oscillations or variations in film speed which are deleterious to good sound recording or reproduction. Thus, to prevent these oscillations, the energy should preferably be absorbed by the damper as fast as it is released. This is accomplished by placing a drag on the tensioning means which will absorb its stored energy.

The damper must also absorb the energy arising from surges entering the system when normally operating. We can assume for illustration, surges of a higher velocity than that encountered in starting. Now since the counterforce of the damper of this invention increases less rapidly than the velocity, we minimize the transfer of energy to the flywheel, store it in the tensioning means, and dissipate it at the low free period velocities of the system.

An object of the invention therefore is to obtain a substantially constant counterforce to film speed changes over a definite range of speed variations and a counterforce proportional to velocity below this range.

This object is accomplished by providing a sliding friction damper in a film loop between the drive sprocket and flywheel roller, which damper has negligible static friction, a counterforce proportional to velocity for a predetermined low range of velocities and substantially constant counterforce for a predetermined higher range of velocities.

One set of materials providing the proper sliding friction characteristic was found to be soft felt against stainless steel polished to a very high degree. A device employing these materials and constructed to operate with a roller positioned in a loop in the film between the drive sprocket and flywheel roller of a sound recording or reproducing machine was found to provide a much superior damper for a film motion filter than the viscous type previously known in the art. It was found that by adjusting the pressure between the felt and the steel, the proper damping could be obtained to dissipate the starting surge before

completing the first oscillation of the mechanical filter and hence in a much shorter time than possible with the oil type damper.

With the oil damper, provision against oil leakage and change in viscosity with temperature had to be provided. The present invention avoids these provisions, is rugged in construction, and may be conveniently adjusted by a screw for controlling the pressure between the felt and the steel to change the damping. A coil spring maintains the pressure between the felt and steel substantially uniform.

The details of the invention will be more fully understood by reference to the accompanying drawing, in which

Fig. 1 is a partial elevational view of a sound reproducer embodying the invention.

Fig. 2 is a front elevational view of the sliding friction damper shown in Fig. 1.

Fig. 3 is a cross-sectional view taken along the line 3—3 of Fig. 2.

Fig. 4 is a rear elevational view of the sliding friction damper.

Fig. 5 is an elevational view of the damper taken along the line 5—5 of Fig. 3; and

Fig. 6 is a graph showing the relationship between the counterforce of friction and velocity for different dampers.

Referring now to the figures, in which the same numeral indicates identical elements, the sound reproducer of Fig. 1 is included in a housing 5 divided into two sections 6 and 7. Section 6 encloses a lamp 10 of constant intensity, the light rays therefrom being projected through a lens and slit assembly tube 11 into compartment 35 7. In compartment 7 a film 13 is continuously advanced through the light beam from tube 11, the driving force being applied by a sprocket 14 having a pad roller 15 associated therewith. The film is pulled by the right hand side of the 40 sprocket, under a roller 16, over a roller 18, under a tension roller 20, over a roller 21, around the flywheel roller or spool 22 having a guide or pressure roller 23 associated therewith, around a roller 24 and then from the left hand side of 45 sprocket 14 which feeds the film 13 to form a slight upper loop between rollers 23 and 24. The roller or spool 22 is mounted on the same shaft with the flywheel shown by the dotted lines 27.

An optical system 28 and photo-sensitive device 50 38 projects the emergent light from the sound track portion of the film 13 and translates it into electrical currents, respectively, as is well known in the art. The particular system shown at 28 and 38 in combination with the spool 22, is disclosed and claimed in my co-pending application Serial No. 54,885 filed December 17, 1935.

The present invention utilizes the damper shown as a unit at 32 and having an arm 33 extending therefrom to the roller 20. A tension spring 35 attached to arm 33 and to lever 36 pivoted at 42 and having a notch and screw adjustment arrangement 37, provides the means of varying the tension on the arm 33.

Referring now to the details of the film motion 65 damper shown in Figs. 2 to 5 inclusive, the arm 33 is fixedly attached to a shaft 38 through a hub 34, the shaft having mounted thereon a light metal plate 39. Attached to the plate 39 in any suitable manner such as by glue or coupled 70 by roughening the surface of plate 39, is a soft felt pad 40. A cup-shaped housing 48 encloses the plate 39 and felt 40 and also a stainless steel plate 41 pressed into the bottom of the cup. This plate is polished preferably by rotary mo- 75

tion to a very high degree on the side thereof contacting felt 40. The felt 40 and plate 41 have a motion relative to one another to provide the sliding friction characteristic of the invention, the static friction therebetween being less than the kinetic friction, although satisfactory operation is obtainable with materials in which these frictions are equal in value. Other materials or constructions having similar characteristics may, therefore, be used.

To maintain a uniform pressure between the plate 41 and felt 40, a coil spring 43 is employed, one end of which abuts the end of shaft 38 and the other end of which is fitted into a notch of a lever arm 44 pivoted on a projection 45. The lever arm 44 may be adjusted to increase or decrease the compression of spring 43 and consequently the pressure between plate 41 and felt 40, by a long screw 46 threaded through a back plate 47 of the casing or housing 48. This particular arrangement permits the adjustment to be made from the front of the reproducer. As shown in Fig. 5, the steel plate 39 and felt 40 have V-type slots 49 provided therein to permit oscillation of the shaft 38. The back plate 47 is attached to the casing 48 by means of a plurality of screws 51 while the entire unit is fixed against rotation by attachment to the frame or housing 5 by screws 31 through holes 31' in the casing 48.

It will be seen in Fig. 1 that the film advanced by the sprocket 14 drives or rotates the spool 22 and the flywheel 27. In starting a sudden tension is placed on the film 13 between the sprocket 14 and the spool 22 which pulls the arm 33 upward, decreases the loop and stores energy in the tensioning spring 35.

Referring now to Fig. 6 in which the counter-force of friction "F" of the damper is plotted against the relative velocities "V" of the friction surfaces of the damper caused by film speed variations or surges, there is shown a pair of dotted lines "B" and "B1" which illustrate the action of two usual types of sliding friction resistance, a pair of dot and dash lines "A" and "A1" which illustrate the action of two viscous types of dampers, and a solid line "I" illustrating the action of an ideal damper of this invention. These curves may be considered as the force-velocity characteristics of different types of dampers.

It will be observed from curve "I" that the slope is initially steep so that adequate damping is obtained at the low velocities which are encountered in the free period oscillation. For higher velocities the slope rapidly decreases so that rapid surges do not generate high counter-forces which accelerate the flywheel or cause slipping of the film on the drum or spool. Now, in curve "A", which illustrates a viscous type damper adjusted to rapidly damp the free period oscillation, there will be unduly high counter-forces offered to high velocity surges which will cause appreciable acceleration of the flywheel or slippage of the film. While the latter objection is eliminated with curve "A1", the damping in this case would not be sufficient.

In the case of curves "B" and "B1" where the usual characteristics of sliding friction are illustrated, there are abrupt changes in counter-force wherever the velocity passes through zero. These changes set up transient surges which are objectionable in film drive filters.

What is claimed is:

1. In a film drive system, the combination of a drive sprocket, a stabilizing means adapted

to be driven by a film advanced by said sprocket, said film having a loop therein between said drive sprocket and said means, said loop varying in size in accordance with variations in speed of said film, and means including a sliding friction damper located in said loop and offering a substantially constant counterforce to said variations in the size of said loop over a certain range of velocities of variations and proportional counterforces to variations in velocities outside of said range.

2. A film drive system comprising a continuously driven sprocket, a flywheel roller, means for guiding the film between said roller and said sprocket in the form of a loop tending to move said guiding means during changes in speed of said film, and means including a sliding friction damper movable by said guiding means for introducing a substantially constant counterforce to changes in speed of said film within a predetermined range and proportional counterforces to changes in speed of said film below said range.

3. A film motion damper comprising a steel plate, felt material positioned in contact with said plate and adapted to be oscillated, means for adjusting the pressure between said felt and said plate, and means interconnecting a moving film and said felt for oscillating said felt, the friction between said felt and said plate constituting a counterforce to variations in speed of said film.

4. A film drive system comprising means for driving a motion picture film at a substantially constant speed, means adapted to be rotated by a film, means between said driving means and said rotatable means for forming a loop in said film, means attached to said loop forming means and adapted to be displaced by changes in speed of said film, and a sliding friction damper including a metal, and soft pliable material in contact therewith, for resisting the displacement of said loop forming means and preventing speed changes from affecting said rotatable means.

5. A film drive system comprising a drive sprocket for a motion picture film, means adapted to be driven by the pull of said film for stabilizing the motion thereof, and a sliding friction damper interposed between said sprocket and said stabilizing means for reacting to changes in motion of said film at a substantially constant counterforce and negligible static friction.

6. A film drive system in accordance with claim 5 in which said sliding friction damper includes steel in contact with soft felt, said damper having a resilient restoring member.

7. A film drive system comprising a sprocket adapted to advance a film at a substantially constant speed, a stabilizing device adapted to be rotated by the pull of said film, said device having considerable mass, and means including a sliding friction damper intermediate said sprocket and said device and adapted to be displaced by speed variations of said film, said means providing a substantially constant counterforce to displacement for variations in speed of said film at different amplitudes and frequencies within a certain range of amplitudes and frequencies.

8. A film drive in accordance with claim 7 in which said sliding friction damper includes soft felt and steel adapted to be moved by film speed variations relatively to one another, the pressure therebetween being controllable.

9. In a film drive system the combination of a tension roller adapted to engage a loop in the film and a sliding friction brake device operated by

movements of said roller, said device having a lower static friction than kinetic friction.

10. A film drive system comprising means for continuously advancing a film, means for stabilizing the movement of said film, and a sliding friction damper in a loop of said film and directly operative by changes in size of said loop for absorbing film speed variations and oscillations of said stabilizing means, the counterforce required to initiate motion of the damper being equal to or less than the force required to maintain motion.

11. A film drive system in accordance with claim 10 which comprises means for increasing the counterforce of friction of said damper required to maintain motion thereof to a value sufficient to dissipate the energy of said speed

variations within the time of one oscillation of said stabilizing means.

12. A drive system comprising a source of power, a mass adapted to be rotated by said power, resilient means adapted to store and release energy during variations in speed of said source of power, and a sliding friction damper connected to said resilient means, the rate of absorption of energy by said damper being proportional to certain velocities of movement of said resilient means and constant to certain other velocities of movement of said resilient means.

13. A drive system in accordance with claim 12 in which said sliding friction damper comprises felt and steel in contact with one another.
